CLAIM

(51) LOC (10) Cl. **08-05**

The ornamental design for a shaped carrying and hanging
attachment hook, as shown and described.

(52) U.S. Cl.

DESCRIPTION

USPC **D8/367**

FIG. 1 is an isometric front perspective view of a shaped
carrying and hanging attachment hook in a typical environment;

(58) **Field of Classification Search**

FIG. 2 is front view thereof;

CPC F16B 45/00; F16B 15/02; F16B 13/10;
F16D 13/041

FIG. 3 is a rear view thereof, showing the face opposite that of
the hook in FIG. 2;

USPC D8/367; 248/301-304, 215

FIG. 4 is a side view thereof;

See application file for complete search history.

FIG. 5 is side view thereof, showing the side opposite that
shown in FIG. 4;

FIG. 6 is a top view thereof; and,

FIG. 7 is a bottom view thereof, showing the side opposite
that shown in FIG. 6.

The broken lines in the Figures are for the purpose of illus-
trating exemplary environmental structure and form no part
of the claimed design.
